UNITED STATES PATENT OFFICE

160,579

BELT BUCKLE OR SIMILAR ARTICLE

Edmund A. Davis, Attleboro, Mass., assignor to
The Robbins Company, Attleboro, Mass., a corporation of Massachusetts

Application May 3, 1950, Serial No. 9,678

Term of patent 7 years

(Cl. D17—1)

To all whom it may concern:

Be it known that I, Edmund A. Davis, a citizen of the United States, residing in the city of Attleboro, county of Bristol, and Commonwealth of Massachusetts, have invented a new, original, and ornamental Design for a Belt Buckle or Similar Article, of which the following is a specification, reference being had to the accompanying drawing, forming a part thereof.

Fig. 1 is a front elevational view of a belt buckle embodying my new design; and

Fig. 2 is an edge view thereof.

I claim:

The ornamental design for a belt buckle or similar article, substantially as shown.

EDMUND A. DAVIS.
